UNITED STATES PATENT OFFICE.

JOHN Q. SHERMAN, OF DAYTON, OHIO.

AUTOGRAPHIC REGISTER.

Application filed May 15, 1920. Serial No. 381,626.

- My invention relates to devices employed for the duplication of autographic notations ordinarily by means of carbon paper, and of this class of machines, known as autographic registers I prefer to apply it to that type wherein successively and correspondingly punched strips of paper are fed by means of pin wheels having pins thereon to engage in the said holes.
- 10 I do not wish to limit my invention to any particular type of manifolding machine, as many of the features thereof will be found applicable to manifolding machines in general.
- 15 The essential object of my invention is to provide a manifolding machine wherein a frame-work may be used, carrying the operating parts of the paper feeding devices, and a cabinet or cover is used to enclose these parts. Among other things I aim to provide a cover which carries thereon the handle for operating paper feeding devices, said handle being controlled by stops also mounted on the cover. I also provide a means for 25 mounting a friction roll to bear on the strips of paper at the feeding line or elsewhere, particularly for the purpose of holding them during tearing off.
- These objects and other advantages to be 30 noted I accomplish by that certain construction and arrangement of parts to be herein-after more specifically pointed out and claimed.
- In the drawings,
- 35 Figure 1 is a perspective view of a machine embodying the features of my invention, same being an autographic register.
- Figure 2 is a detail vertical section view, showing separate from each other, the 40 matching pieces between the cover supported handle and the paper feed shaft in horizontal section.
- Figure 3 is a perspective view of the fitting on the cover supported handle looking 45 at it from the outer side.
- Figure 4 is a like view of the fitting on the paper feed or pin wheel shaft.
- Figure 5 is a detail side elevation of the 50 parts shown in perspective in Figure 4, showing the end of the feed shaft.
- Figure 6 is a detail section taken through the handle stop.
- Figure 7 is a plan view of the handle stop.
- Figure 8 is a side elevation showing the
- handle in position of engagement by the 55 stop.
- Figure 9 is a perspective view showing a register with the cover broken away and the frictional roll holder elevated.
- Figure 10 is a vertical cross section taken 60 through the feeding device, with the feed handle partly turned.
- In the manufacture of autographic registers in particular and manifolding devices in general, there has always been considerable 65 expense involved in obtaining a nice finish to the exposed parts particularly since the parts are necessarily somewhat complex and if exposed require considerable care in their finish.
- 70 It is the basic object of my invention to provide a construction of autographic register or other manifolders wherein the operating parts are not exposed, but wherein, on the contrary, a cabinet or cover is provided 75 which provides all of the proper clearances and covers all of the operating parts but the handle and the exposed writing surface for the paper.
- In the embodiment of the mechanism illustrating my invention herein the effort has been to supply the necessary features in connection with handle mounting and operation, frictional roll mounting, operation and clearance, and removability for the cabinet 80 or cover without dismantling the machine in any degree.
- 85 I will not dwell upon the advantages of the cabinet form of machine, which lie in ease of paper mounting, dust proofness and 90 simplicity of manufacture, as these are self evident to those skilled in the art.
- 95 As shown in Figure 9 the framework 1 is set inside of a cabinet 2 on a base 3 and will be understood to embody all of the necessary features of a pin wheel paper feed machine. The pin wheels are shown at 4, the paper roll spindle mounting slots at 5, the tablet plate at 6 and the friction roll controlling cams at 7.
- 100 The feed shaft 8 of the machine is mounted in this framework and carries the pin wheels and roll controlled cams thereon and is fitted at its end with a special structure which will be described. The pin wheels are of a size to project their pins through slots 9 in the tablet plate or in any desired extensions from the tablet plate, and the cams 7

protrude also through suitable slots in the said tablet plate or its extensions.

The cabinet is of a size to cover the entire mechanism and is formed with an opening at 5 10 to expose the paper for reception of autographic notations. The cabinet is also formed with a ridge 11 across it, at the point of location of the paper feed engagement for the purpose of clearance of the 10 friction roll, to be described.

The friction roll is employed in a number of different forms of feed in autographic registers and the like, in order to keep the paper in a tight grasp at the desired periods 15 during the operation of the machine. In order to provide a friction roll device which will not require a special construction in the cabinet itself, I provide a small semi-cylindrical housing 12 which is slotted at the ends 20 at 13, and turned under at 14, so as to provide a retaining slot for the reduced ends 15 of the friction roll 16.

The friction roll is shown as cut away at 17 to provide a clearance for the feed pins, 25 and I prefer that some sort of spring device be employed in the housing to press against the ends of the roller and force the said ends downwardly in the slots 13.

The structure now described, I hinge to 30 the framework of the machine, by means of a hinge 18 or in any other desired manner, so that the whole friction device can be swung out of the way for access to the parts beneath. The ridge in the cabinet which has 35 been referred to fits down over the housing 12 with proper clearance thereof. Should it be desired to omit the pressure roll, however, and adopt the construction of my Patent 1,259,918, of March 19, 1918, this can 40 readily be accomplished and the ridge in the cabinet altered into the form shown at 24, 24 in Figure 3 of the drawings of said patent. The housing is held down to the framework by means of a clip 12^a hinged 45 on the framework and adapted to engage lugs 12^b. Using the same hinge and clips, I may employ a mere bar instead of the housing and roller, same being cut away to clear the feed pins. The end of the feed 50 shaft is equipped with a special fitting which will receive the feed handle in exactly accurate relation. This fitting comprises a triangular plate 19, having flanges 20, 20, at two sides thereof, but is open at one side, 55 said plate having a recess 21 centrally thereof, for the reception of a centering and retaining pin.

The cabinet is equipped with the handle 60 22 which is free to revolve therein but which has on its end inside of the cabinet a triangular plate 23 adapted to slide into and fit between the flanges of the plate 19, said plate having a central boss 24 formed at its center, which boss is mounted over the inwardly protruding portion 23^a of the handle,

A pin 25 is mounted slidably in the handle and extends through this boss, being under the influence of a spring 26 which presses said pin inwardly into the recess 21 in the plate 19. 70

With this construction when the cabinet is brought down over the framework, the paper feed shaft is adjusted to receive the handle attachments. The handle will thus move into place and the pin 25 will hold 75 the parts together until manually withdrawn by means of its knurled head 27.

The handle has a stop for holding it in fixed position both against clockwise and counterclockwise play, so that when it is 80 brought down together with the cabinet it will locate the feed shaft exactly at the desired point for the end of each complete operation of the feeding devices. It has also a back throw stop in addition. 85

These stops are mounted in a small housing 28, secured to the outside of the cabinet and having a spring-pressed pin 29 positioned to act as a stop in reverse to the feeding movement, and a spring-pressed pin 90 30 positioned to engage in a recess 31 in the under side of the handle.

The pin 30 has projected laterally from it an operating stud 32, which extends out through a slot in the housing, and is capable 95 of a sliding movement to carry the pin 30 into and out of position of engagement with the recess in the handle.

During each complete rotation of the handle it is free to move, but when it completes a full rotation it is caught by the pin 30 and just prior to being so caught it snaps past the back throw pin 29, thereby coming into a rigid locked position. To release it the operator must depress the stud 32, thereby lowering the pin 30 from contact position. Even when he does release this pin, however, the pin 29 prevents back throw so 100 that a slip on the part of the operator cannot result in a clogging up of the paper. 105

It is evident from the above that I have provided a cabinet machine, wherein the cabinet forms a separate part from the framework and mechanism generally, but in which the operating handle is carried on the cabinet itself, and has a special form of connection with the feed shaft for the paper. Furthermore the cabinet carries the operating handle stop, as well as the handle, thereby 115 relieving the cabinet from the necessity of being slotted except at the writing point and at the necessary point in advance of the paper feed to permit the issued strips to pass out, as shown at 35 (Fig. 1). The fittings for the handle and feed shaft might be reversed or other forms provided as the ones shown are merely a preferred embodiment. 120

It has been my object above to describe 125 a complete embodiment of my novel mecha- 130

nism for the purpose of illustrating my invention and not for the purpose of limiting the construction of the claims that follow to the exact form of device so described.

5 Having thus described my invention what I claim as new and desire to secure by Letters Patent, is:—

1. In a machine of the character described, the combination with a framework, a feed 10 shaft therein, and a cabinet having side walls adapted to come down over the framework and cover it, of a handle for operating the feed shaft, and means on the handle and the shaft to come into engagement upon 15 closing the cabinet over the framework, said handle being secured on the cabinet.

2. In a machine of the character described, the combination with a framework, a feed shaft therein and a cabinet having side 20 walls adapted to come down over the framework and cover it, of a handle for operating the feed shaft, means on the shaft and handle to engage each other upon positioning of the cabinet, and additional means to lock 25 said connection against separation, said handle being secured on the cabinet.

3. In a machine of the character described, the combination with a framework, a feed 30 shaft therein and a cabinet having side walls adapted to come down over the framework and cover it, of a handle for operating the feed shaft, means on the shaft and handle to engage each other upon positioning of the cabinet, and additional means to lock 35 said connection against separation, said latter means comprising a spring pressed member adapted to engage the shaft and handle on a horizontal line thereby preventing vertical lifting of the cabinet with relation to 40 the framework.

4. In a machine of the character described, the combination with a framework, a feed shaft therein, and a cabinet having side walls adapted to come down over the framework 45 and cover it, of a handle for operating the feed shaft and means on the shaft and handle to engage each other upon positioning of the cabinet, and additional means to lock 50 said connection against separation, comprising a spring pin held in the handle and said shaft having a socket for receiving the said spring pin.

5. In a machine of the character described, the combination with a framework, a feed 55 shaft therein, and a cabinet having side walls adapted to come down over the framework and cover it, said cabinet being removable as a unit, of a handle on the cabinet for operating the feed shaft, and means on the 60 handle and the shaft to come into engagement upon closing the cabinet over the framework, and releasable means on the cabinet as distinguished from the framework 65 for locking the handle at a desired position.

6. In a machine of the character described,

the combination with a framework, a feed shaft therein, and a cabinet having side walls adapted to come down over the framework and cover it, said cabinet being removable as a unit, of a handle on the cabinet for 70 operating the feed shaft, and means on the handle and the shaft to come into engagement upon closing the cabinet over the framework, and releasable means on the cabinet as distinguished from the framework 75 for locking the handle at a desired position, against both clockwise and counterclockwise rotation.

7. In a machine of the character described, the combination with a framework, a feed 80 shaft therein, and a cabinet having side walls adapted to come down over the framework and cover it, said cabinet being removable as a unit, of a handle on the cabinet for operating the feed shaft, and means on the handle and the shaft to come into engagement upon closing the cabinet over the framework, and releasable means on the cabinet as distinguished from the framework 85 for locking the handle at a desired position, comprising a spring member adapted to project itself in the path of the handle, and the handle having a socket to receive said pin.

8. In a machine of the character described, the combination with a framework, a feed shaft therein, and a cabinet having side walls adapted to come down over the framework and cover it, of a handle for operating the feed shaft, and means on the handle and the shaft to come into engagement upon closing the cabinet over the framework, and releasable means on the cabinet for locking the handle at the desired position, against 100 both clockwise and counterclockwise rotation, comprising a housing adapted for mounting on the outside of the cabinet, a spring pin in the housing having means for manually depressing it, and an additional spring pin in the housing set in a different 105 vertical plane from the first noted spring pin.

9. In a machine of the character described, the combination with a framework, a feed shaft therein, and a cabinet having side walls adapted to come down over the framework and cover it, of a handle for operating the feed shaft, and means on the handle and the shaft to come into engagement upon closing the cabinet over the framework, comprising a triangular plate on the shaft, a triangular plate on the handle, one of said plates having flanges adapted to form a seat for the other plate on two sides thereof, but having no flange on one side thereby permitting the unflanged plate to slide into position.

10. In a machine of the character described, the combination with a framework, a feed shaft therein, and a cabinet having

side walls adapted to come down over the framework and cover it, of a handle for operating the feed shaft, and means on the handle and the shaft to come into engagement upon closing the cabinet over the framework, comprising a triangular plate on the shaft, a triangular plate on the handle, one of said plates having flanges adapted to form a seat for the other plate on two sides thereof, but having no flange on one side, thereby permitting the unflanged plate to slide into position, one of said plates having a socket therein and a pin in the other plate to move into the said socket thereby locking the connection.

11. In a machine of the character described, the combination with a framework, a feed shaft therein, and a cabinet having side walls adapted to come down over the framework and cover it, of a handle for operating the feed shaft, and means on the handle and the shaft to come into engagement upon closing the cabinet over the framework, in one position only of said shaft and handle respectively.

12. In a machine of the character described, the combination with a framework, a feed shaft therein, and a cabinet having side walls adapted to come down over the framework and cover it, of a handle on the cabinet for operating the feed shaft, and means on the handle and the shaft to come into engagement upon closing the cabinet over the framework, in one position only of said shaft and handle respectively, and means for releasably locking the handle in a single position on the cabinet.

13. In a machine of the character described, the combination with a framework, a feed shaft therein, of a handle for operating the feed shaft and means on the handle and the shaft to come into engagement, comprising a triangular plate on the shaft, a triangular plate on the handle, one of said plates having flanges adapted to form a seat for the other plate on two sides thereof, but having no flange on one side, thereby permitting the unflanged plate to

slide into position, one of said plates having a socket therein and a pin in the other plate to move into the said socket thereby locking the connection.

14. A handle lock for manifolding registers which comprises in combination with a socketed handle, a spring pin to engage in the socket, of the handle, means to release the pin, and an additional stop adapted to engage the handle upon revolution in the wrong direction, but permitting it to pass in the correct direction and positioned so that upon the release of the first pin the operator may not impart an accidental improper movement to the handle.

15. A handle lock for manifolding registers which comprises in combination with a socketed handle, a spring pin to engage in the socket of the handle, means to release the pin, and an additional stop adapted to engage the handle upon revolution in the wrong direction, but permitting it to pass in the correct direction and positioned so that upon the release of the first pin the operator may not impart an accidental improper movement to the handle, this additional stop being positioned to engage the side of the handle when the latter is in engagement with the spring pin.

16. A handle stop for autographic registers comprising a stop, adapted to automatically engage and hold the handle against operation in either direction, and an additional stop adapted to engage the handle in one direction only and positioned to prevent an improper movement upon release of the first stop.

17. In an autographic register, the combination with a pin wheel feed for paper having a driving shaft, a frame in which the shaft and feed are mounted, and a cabinet mounting means for the cabinet whereby it is adapted to come down over the feed, said cabinet having formed thereon clearance portions for that portion of the pin wheel feed that is adapted to keep the paper on the feed pins.

JOHN Q. SHERMAN.
